UNITED STATES PATENT OFFICE.

RAY L. REHART, OF GLENDALE, CALIFORNIA.

CALF-WHEEL SHAFT.

Application filed March 12, 1923. Serial No. 624,441.

To all whom it may concern:

Be it known that I, RAY L. REHART, a citizen of the United States, and resident of Glendale, in the county of Los Angeles and State of California, have invented new and useful Improvements in a Calf-Wheel Shaft, of which the following is a specification.

This invention relates to a reel for winding cable or rope thereon and pertains more especially to a reel so arranged that the cable or rope is fed off center.

The device disclosed herein as embodying the invention is what is commonly known as a calf wheel employed in well drilling. This well or reel is used for lowering and pulling casing. The crown pulley is disposed at the top center of the derrick and the drilling cable is passed thereover. The bull wheel on which is wound the drilling cable is disposed in the derrick so that the reel is centered with respect to the crown block, and the cable spools thereon with ease. The calf wheel, however, is disposed on one side of the derrick creating a side pull on the cable. In order to make the cable spool thereon, it has been the custom to tilt the reel or shaft with respect to the horizontal so that the cable will wind upon the surface of the shaft normal to its axis and will not climb.

Tilting the shaft is accomplished by lowering one of the bearings and this produces a tilted wheel. The calf wheel drive rope or chain passing over the tilted calf wheel has a tendency to run off the rim thereby creating trouble. The primary object of this invention is to provide a tapered shaft serving as a reel and having a degree of taper such as to provide for correct spooling of the cable and to keep the calf wheel straight.

These objects together with other objects and corresponding accomplishments are obtained by means of the embodiment of my invention illustrated in the accompanying drawing, in which:

Fig. 1 is a side elevation of a calf wheel; Fig. 2 is a front elevation; and Fig. 3 is a diagrammatic plan view of a drilling rig with my improved calf wheel structure mounted therein.

The details of the construction of the wheels, spooling flanges and gudgeons as well as other elements of the structure are not material to this invention. Certain of the details shown herein are for illustrative purposes only.

A tapered shaft 3 may be provided adjacent its small end with a cylindrical portion, upon which the hub 4 of the wheel may be pressed or otherwise secured thereto. The shaft is preferably hollow and has pressed into the small end thereof a calf wheel gudgeon 5. Pressed into the other end of the shaft is a spool gudgeon 6. A flange of the spool gudgeon serves as one flange for the reel, while the hub serves as the other flange.

Built up upon the hub 4 by means of arms, braces, and cants is the calf wheel 7. As shown herein, there is a sprocket rim 8 attached to the wheel. However, a grooved rim may be used. The details of assembly of the calf wheel are not material to the present invention.

The calf wheel A and shaft are placed in position in the derrick the floor thereof being indicated by B with the gudgeons in horizontal alignment, the smaller end of the shaft being at the further end from the crown block. The bull wheel C is in line with the crown pulley D. It is obvious that the pull upon the cable will then be substantially normal to the surface elements of the calf wheel shaft. In this position, the cable spools upon the shaft without climbing. Furthermore, the calf wheel may be in line with the driving wheel of the rig so that there is no tendency for the sprocket chain to run off the sprocket.

What I claim is:

In a drilling rig having a crown pulley centrally disposed, a calf wheel disposed to one side of said crown pulley, said calf wheel comprising a tapered shaft having a drive wheel mounted on the smaller end thereof, said drive wheel having its plane disposed normal to the axis of said shaft.

In witness that I claim the foregoing I have hereunto subscribed my name this 27th day of February, 1923.

RAY L. REHART.
